US00D883737S

(12) **United States Design Patent** (10) **Patent No.:** **US D883,737 S**
(45) **Date of Patent:** **** May 12, 2020**

(54) **LID**

(71) Applicant: **YETI Coolers, LLC**, Austin, TX (US)

(72) Inventors: **Dustin Bullock**, Austin, TX (US);
Steve Charles Nichols, Austin, TX (US);
Edward Abante, Austin, TX (US);
Evan Goldberg, Austin, TX (US)

(73) Assignee: **YETI Coolers, LLC**, Austin, TX (US)

(***) Term: **15 Years**

(21) Appl. No.: **29/667,018**

(22) Filed: **Oct. 17, 2018**

(51) **LOC (12) Cl.** **07-01**

(52) **U.S. Cl.**

USPC **D7/396.2**

(58) **Field of Classification Search**

USPC D7/392, 392.1, 396.2; D9/434–436, 443,
D9/447, 449, 454, 499, 439, 440

CPC A47G 21/18; A47G 19/2266

CLAIM

The ornamental design for a lid, as shown and described.

DESCRIPTION

FIG. 1 is a top, front, right perspective view of a lid showing our new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a top, front, right perspective view of a lid showing our new design in its exemplary environment;

FIG. 9 is a top, front, right perspective exploded view of a lid showing our new design;

FIG. 10 is a front view thereof;

FIG. 11 is a right side view thereof;

FIG. 12 is a rear view thereof;

FIG. 13 is a left side view thereof;

FIG. 14 is a top view thereof;

FIG. 15 is a bottom view thereof; and,

FIG. 16 is a top, front, right perspective exploded view of a lid showing our new design in its exemplary assembly.

The broken lines depicting the remainder of the lid show features that form no part of the claimed design.

1 Claim, 16 Drawing Sheets
